UNITED STATES PATENT OFFICE

161,826

BALL POINT PEN

Fred Ferber, Englewood, N. J.

Application April 30, 1949, Serial No. 2,362

Term of patent 14 years

(Cl. D74—17)

To all whom it may concern:

Be it known that I, Fred Ferber, a citizen of the United States, and a resident of Englewood, in the county of Bergen and State of New Jersey, have invented a new, original, and ornamental Design for Ball Point Pen, of which the following is a specification, reference being had to the accompanying drawings, forming part thereof.

In the drawings:

Fig. 1 is an elevational view of a ball point pen, showing my new design.

Fig. 2 is a top view thereof.

Fig. 3 is a bottom end view of the same.

The design is characterized by three similar side faces each of which is of convex formation extending substantially the entire length of the pen with adjacent side faces merging with each other by a rounded vertex.

I claim:

The ornamental design for a ball point pen, substantially as shown and described.

FRED FERBER.
